UNITED STATES PATENT OFFICE.

HENRI FRANCART, OF TONGRES, BELGIUM.

TUNNEL FURNACE, KILN, OVEN, AND THE LIKE.

Application filed June 24, 1920, Serial No. 391,512. Renewed February 21, 1925.

(GRANTED UNDER THE PROVISIONS OF THE ACT OF MARCH 3, 1921, 41 STAT. L., 1313.)

To all whom it may concern:

Be it known that I, HENRI FRANCART, engineer, citizen of Belgium, residing at Tongres, Belgium, have invented certain new and useful Improvements in or Relating to Tunnel Furnaces, Kilns, Ovens, and the like (for which I have filed an application in England, December 19, 1918, Patent No. 166,198), of which the following is a specification.

The present invention relates to tunnel ovens.

In a well constructed tunnel oven, the articles under treatment are always, in the cooling zone, at a higher temperature than the stationary faces of the walls, whilst in the preheating zone they are always at a lower temperature than at the stationary walls surrounding them.

For the gaseous mass contained in the oven, there is therefore in each section of the oven an ascensional force due to the difference in density of the gaseous medium in contact with one or the other solid body.

The object of the present invention is to utilize this force in such a way as to automatically create a gaseous circulation in order to obtain more economical working and a better output.

The invention is realized by forming one or two inclined passages passing successively through the articles under treatment and along the vertical walls, the pitch of the inclined passage or passages being such that the ascensional forces cause the longitudinal desired displacements.

For one and the same displacement, the inclined pitch will, in the preheating zone, be inverse to that in the cooling zone. This automatic displacement may be used in combination with a draught apparatus in order to conduct the gases to the mouth or entrance of the tunnel oven.

The helical passage or inclined passages may be made of different material and may approach more or less the theoretical helical pitch. With a view of obtaining the maximum effect, it is necessary that each portion of the helix should be so arranged as to localize radiation.

In a tunnel oven this arrangement may be used over the whole length, or over a portion only in flame ovens or in ovens of the muffle type.

According to one method of construction, 55 the heating and cooling zones are formed of a number of compartments, higher and broader than is necessary for the passage of the trucks loaded with the goods to be treated, the separating partitions leaving an 60 opening for the passage of the goods.

From the entrance of the tunnel oven towards the outlet, each chamber, in the pre-heating zone, is in communication at the top with the bottom of the adjoining one, 65 this communication being effected along the wall of the passage.

In the cooling zone, on the contrary, the bottom of each chamber is in communication along the wall with the top of the 70 following chamber.

The inclined passage formed by these passages and the introduction into the oven in sections of the goods to be treated cause an automatic draught which ensures the regular 75 and progressive treatment in each chamber.

The draught of the oven may also be increased by using the same process for the drying zone, care being taken to arrange the burners in the bottom part of the passages 80 along the walls.

If the oven is not very high, which would be the case in ovens for annealing metals, a more or less inclined passage can be obtained by simply forming the partitions which separate the compartments by means of two vertical planes which intersect each other at an angle more or less acute in relation to the centre of the oven. In the cooling zone the angle formed is directed towards the 90 outlet of the oven and in the heating zone towards the entrance.

The accompanying drawings show two constructional forms of the invention by way of example.

Figure 1 is a longitudinal section showing an elevation of the two zones of the tunnel oven.

Figure 2 is a cross section through the heating zone.

Figure 3, drawn to a reduced scale, is a section of a low annealing oven, while Figure 4 is a diagrammatic section plan thereof.

In the arrangement shown in Figs. 1 and 2 the trucks 1 successively traverse the two zones of the oven in the direction shown by the arrow. The upper region of the oven is traversed by vertical partitions 2, which

- divide the tunnel into compartments 2'. Adjacent each wall of the oven and extending from the lower edges of the transverse vertical partitions, are inclined partitions 3. 5 The lower part of these inclined partitions fall immediately under the transverse partition adjacent the one from which it extends. Extending along the inside of the inclined partitions are longitudinal walls 4 which have openings, as indicated by the numeral 5', leading from the main part of the oven into the conduit formed by the inclined partitions 3. From this structure it will be seen that there is formed by means 10 of the longitudinal wall 4, the inclined partitions 3, and the vertical partitions 2 what might be called inclined passages. The gases entering into openings 5, either from the source of gas supply which may be any suitable source, or from the oven through the openings in the longitudinal walls will be given a longitudinal motion by means of the inclined passage formed by the partition 3.
- 15 25 By means of the vertical partition an increased surface is provided for radiation and the localization of the heat. These partitions also aid in directing the heat to the objects that are being treated.
- 30 35 In the preheating zone, each compartment is in communication at the top with the bottom of the following compartment in the direction of the outlet. In the cooling zone, the contrary is the case. By arranging the articles to be treated in the form of successive sections 7 upon the trucks, the helical passage will thus be formed in inverse directions in the two zones.
- 40 45 In the preheating zone the gases entering through the openings 5' ascend first into the central part of the compartment between the partitions 2, traversing the goods and are then directed downwardly through the conduits formed by the inclined partitions 3 toward the bottom of the next compartment and so on. This action takes place on both sides of the oven, as indicated by arrows in Fig. 2.
- 50 55 The device shown and described in this application is merely the preheating and cooling parts of an oven, and describes that part of the oven which may be used in connection with the heating zone of a similar oven shown and described in applicant's co-pending application Serial No. 391,513.
- In working order the gases therefore circulate automatically or by the aid of the draught apparatus from the cooling zone through the heating zone passing successive-

ly through the articles under treatment, thus 60 cooling or heating these latter respectively in a methodical manner.

In the position shown in Figures 3 and 4, characterized by the low height of the oven, use is preferably made of partitions 6 arranged according to two vertical planes intersecting each other in the axis of the oven, so that the gas imprisoned between them and ascending or descending in the central portion 65 will carry along the whole of the gaseous mass in the desired direction.

The arrows marked in full lines in Figure 4 indicate the direction in which the trucks travel; the arrows in broken lines indicate the entrance of the air and the exit of the 70 75 gases respectively.

Having now particularly described and ascertained the nature of my said invention, and in what manner the same is to be performed, I declare that what I claim is:

1. In a tunnel oven, flanges extending across the interior of the oven, forming radiating surfaces and heat localizing spaces, diagonal flanges on each side of the oven extending from the lower part thereof to the 80 first named flange.

2. In a tunnel oven, flanges extending across the interior thereof, forming radiating surfaces and heat localizing spaces, diagonal flanges on each side of the oven extending from the lower part thereof to the first named flanges, said diagonal flanges at 90 one end of the oven slanting in a direction opposite to those at the other end.

3. In a tunnel oven, flanges extending across the interior surface thereof, diagonal flanges connecting the first named flanges to the lower part of the oven and longitudinal partitions joining the diagonal flanges and partly separating the main cavity of the 100 oven from the conduit formed by the diagonal partitions.

4. In a tunnel oven, means extending across the inner surface thereof for the purpose of localizing the heat and increasing the surface of radiation and diagonal means extending from the first named means to the lower part of the oven and means connecting the last named means and forming therewith conduits to direct the product of combustion 110 to the upper part of the oven.

In testimony whereof I affix my signature in presence of two witnesses.

HENRI FRANCART.
